Patented June 14, 1921.

Inventor:

Yule Wm. Rogers.

UNITED STATES PATENT OFFICE.

YUBIE WILLIAM ROGERS, OF ST. LOUIS, MISSOURI.

COMBINATION-CHAIR.

1,381,338.

Specification of Letters Patent. Patented June 14, 1921.

Application filed March 24, 1919, Serial No. 284,828. Renewed May 2, 1921. Serial No. 466,221.

To all whom it may concern:

Be it known that I, YUBIE WILLIAM ROGERS, a citizen of the United States, residing at St. Louis, State of Missouri, have invented a new and useful Combination-Chair, of which the following is a specification.

My invention relates to improvements in combination chairs, in which, the back is elevated on hinges to a table top position; and the object of my invention is to provide a chair or the like, having its back supports in combination with a door leading into an inclosure beneath its seat; the novelty of such an arrangement, being to give immediate access to the compartment beneath said seat and also the convenience of adjusting the back to or from one when it is in a table top position.

I attain this object by the mechanism illustrated in the accompanying drawing in which—Figure 1 is a perspective view of the device when used as a seat at a table, Fig. 2 is a view of the device when used as an ordinary chair. Similar numerals refer to similar parts throughout the two views.

Numeral 1 represents the seat of the de-

vice having a door 2 leading into an inclosure beneath said seat; back supports 3 are secured to door 2, and a back 4 is pivotally secured to the upper ends of supports 3; there is a third support 5 secured to the seat 1 to uphold the free end of back 4 when in a table top position.

When the device is not used as a seat at a table, the door is swung inwardly, carrying the back over support 5 until it falls in the position of an ordinary chair as shown in Fig. 2.

I do not confine myself to the exact arrangements of parts herein shown and described, as many changes may be made without departing from the nature of my invention.

What I claim is—

A combination chair comprising a seat, having a door leading into an inclosure beneath said seat, supports secured to said door, a back pivotally secured to said supports and suitable means for supporting said back when in a table top position, for the purpose described.

YUBIE WILLIAM ROGERS.
